UNITED STATES PATENT OFFICE.

KARL R. SCHUSTER, OF HOPATCONG, NEW JERSEY.

CONCRETE MIXER.

Application filed April 28, 1924. Serial No. 709,483.

This invention is a mixer, wherein provision is made for agitating the ingredients of the mass by the action of fluid pressure conjointly with mechanical agitation, as a result of which the ingredients are expeditiously mixed together in a thorough manner.

In mixing materials to produce a mixture known in the art as concrete, it is usual to employ a more or less coarse mineral aggregate such as broken stone. Such materials when mixed in a vessel into which air is blown to effect the agitation or the "mix", show a tendency to arch across that part of the receptacle into which the air is blown because of the presence of the coarse mineral aggregate within the mixer. This results in the coarse mineral aggregate and other ingredients remaining in a quiescent condition, and the inflowing fluid pressure (air) passes freely in an upward direction and through a passage, or passages, which is formed in, or opened through, such mass by the pressure of the fluid, experience having shown that the broken stone as a component of the mass precludes, at least to a substantial extent, the agitation and mixing of the mass.

According to my invention, the tendency of the broken stone used as a component of the mixture to remain at rest is precluded by mechanical agitation. To this end, my invention embodies, in addition to means for feeding air or gas under pressure, the element of a mechanical agitator, the same being preferably of the rotary type, and being positioned within the lower portion of the receptacle and in the path of the inflowing air or gas so as to be rotated by the impact of such pressure against the surfaces of said agitator, whereby the motion of the agitator taken conjointly with the pressure of the inflowing fluid acts to impart the desired agitation to the mass of material and to insure a thorough admixture of the ingredients. Said agitator element performs the function, primarily, of precluding lodgment of the broken stone so as to remain in a state of rest within the lower part of the receptacle, and the motion of said agitator element is secondary to the action of the inflowing fluid the pressure of which against the components of the mass imparts motion to the components necessary to effect the intimate admixture thereof.

Other features and advantages of the in-

vention will appear from the following description taken in connection with the drawings, wherein—

Figure 1 is a vertical section of a concrete mixer embodying this invention, and

Figure 2 is a plan thereof.

In the constructional form shown in the drawings, the mixing receptacle A is provided with a curved bottom a. Attached to the bottom is a tubular member B for feeding air or gas under pressure interiorly of the receptacle. As shown, this tubular member terminates in a nozzle b attached to the curved bottom a at one side of the vertical axis of said receptacle, said nozzle b constituting the pressure inlet to the chamber of the receptacle eccentrically thereto. The tubular member is shown as having elbows b' forming components of a pipe which consists of sections united by a separable coupling c. It is apparent that the tubular member may be supplied with air or gas from a reservoir, a pump, or other source of supply.

C designates an agitator element positioned within the lower portion of the mixing receptacle and movable therein for the purpose of operating conjointly with the fluid pressure in agitating the components of a mass with a view to mixing the same. In the constructional form of the agitator element it embodies a horizontal shaft d, a plurality of radial arms d', and blades d², all attached so as to constitute a unitary structure. The shaft d of said agitator is mounted in bearings e attached to opposite side walls of the receptacle. The agitator is positioned within the lower part of the receptacle so that the curved bottom a is concentric to the axis of the shaft d, and thus the agitator is mounted for rotatable movement within the receptacle for the blades or paddles d² to sweep close to the inner surface of the curved bottom a of said mixing receptacle.

It is apparent that the agitator may be rotated in any desired way, but in the present invention it is preferred to utilize the pressure of the inflowing air or gas for the purpose of imparting rotative movement to the agitator. As shown in Figure 1, the blades or paddles d² of the agitator pass over the inlet b and in close relation thereto, so that the inflowing air or gas will act against the blades, thus supplying the motive power for the rotation of the agitator.

I have elected to show my present invention in connection with a mixer such as is disclosed in my prior Patent No. 1,111,974, but it will be understood that the invention 5 may be employed in connection with other appropriate forms of mixing apparatus, such as that disclosed in my copending applications filed December 6, 1919, Serial No. 343,037 and Serial No. 88,770, filed April 4, 10 1916. In the constructional form of apparatus shown in the drawings, the mixing receptacle A is provided at its opposite sides with trunnions f', the latter trunnion f' being hollow, and said trunnions are journaled in suitable bearings g of a supporting frame G. To the hollow trunnion is attached an internally toothed gear h with which meshes a gear pinion h' on a shaft H having a crank h² for its operation, 15 whereby hand-power may be applied for imparting rotative movement to the pivotally mounted mixing receptacle A. The pressure required for the mixing operation is furnished through a pipe I provided with a cock i and with a branch i', the latter entering the hollow trunnion f' and having tight fitting engagement therewith due to the use of a gland or stuffing box z'. The tubular member B is in communication with 20 a hollow journal f', and thus the tubular member is at all times in operative relation to the hollow journal and to the mixing receptacle so that the tilting movement of said mixing receptacle will not interrupt the 25 communication between the tubular member B and the feed pipe I, for the reason that said tubular member partakes of the tilting movement of the receptacle and during such movement the communication between 30 the tubular member B and the pipe I is obtained through the hollow trunnion f' and the branch pipe i'.

The operation of the mixer will be apparent from the description, but may be 45 summarized briefly as follows:

The components of the mass to be mixed are dumped into the receptacle, and the cock i is opened to allow steam, air or gas to flow from the pipe I and its branch i' 50 through the trunnion f' and the tubular member B so as to flow into the chamber of the receptacle A. The inflowing steam, air or gas under pressure agitates the mass of material within the receptacle and the 55 pressure of such fluid acts upon the blades of the agitator for the purpose of rotating the latter within the receptacle. The agitator acts conjointly with the fluid pressure for imparting motion to the components 60 of the mass so as to effect the mixing thereof. The valve i should be kept open during the mixing operation for feeding the fluid under pressure. Obviously, water is supplied as and when required. To discharge the 65 mixed mass from the apparatus shown, the

valve i is closed and the operator turns the crank h² to turn the receptacle A into a downwardly inclined position, thereby discharging the mixed mass by gravity.

Having thus fully described the invention, 70 what I claim as new and desire to secure by Letters Patent is:

1. In a mixer, a dumpable receptacle, an agitator mounted within said receptacle and movable therewith in the discharge of a 75 mixed mass therefrom, and means for feeding fluid under pressure, whereby the energy of said fluid is utilized for rotating said agitator and for agitating the materials composing the mass within the receptacle. 80

2. In a mixer, a dumpable receptacle, means for feeding fluid under pressure to the interior of said receptacle, and a rotary mixer element mounted within the receptacle and positioned in the line of flow of the fluid under pressure, whereby the energy of the fluid is utilized for imparting rotative movement to the mixer element and for effecting the admixture of the components of a mass within said receptacle, said mixer element 90 being carried by said receptacle for movement therewith in the operation of discharging the mixed mass from said receptacle. 95

3. In a mixer, a receptacle mounted for movement on a horizontal axis and adapted for a bodily dumping movement in discharging a mixed mass therefrom, means for feeding fluid under pressure to the interior of said receptacle, and a mixer element mounted for movement within said receptacle substantially below the axis of movement of the receptacle itself, said mixer element being exposed to the energy of the fluid and said mixer element and the inflowing fluid acting conjointly in the agitation 100 of a mass for effecting the admixture thereof prior to the dumping movement of said receptacle. 105

4. In a mixer, a receptacle pivoted for dumping movement on a horizontal axis for effecting the discharge of a mixed mass therefrom, a mixer element supported within the receptacle for movement relatively thereto, and means for feeding a fluid under pressure to the interior of said receptacle, 115 whereby the energy of the fluid is utilized for imparting motion to the mixer element and said inflowing fluid and the mixer element act conjointly in effecting the admixture of the mass within the receptacle, said mixer element and the fluid pressure means being movable with said receptacle in the discharge of the mixed mass therefrom. 120

5. In a mixer, a pivoted receptacle adapted for bodily movement in discharging a 125 mixed mass therefrom, means for feeding a fluid under pressure to the interior of said receptacle, and a mixer element rotatable within the receptacle under the energy of the fluid pressure supplied to the receptacle, 130

said mixer element and the fluid pressure means being movable with said receptacle upon the movement thereof to and from a discharging position.

- 5 6. In a mixer, a receptacle having an arcuate bottom and an open top, said receptacle being bodily movable to and from a position wherein a mixed mass is adapted to be discharged through said open top, 10 means for feeding fluid under pressure to the interior of said receptacle, and a mixer element mounted within the receptacle for rotation on an axis substantially concentric to the arcuate bottom, said mixer element 15 being carried by said receptacle and positioned therein for exposure to the inflowing fluid pressure, whereby the energy of the admitted fluid is adapted to be expended for mixing the mass and for imparting rotative 20 motion to the mixer element.

7. In a mixer, a tiltable receptacle supported by trunnions one of which is substantially hollow, a mixer element mounted within the receptacle for rotation therein, 25 and means connected with the receptacle and with said hollow trunnion for feeding fluid under pressure to the interior of said receptacle, said fluid feeding means and said mixer element being movable with said receptacle in the movement of the latter for discharging a mixed mass therefrom.

8. In a mixer, a receptacle supported by trunnions one of which is hollow, a pressure pipe attached to the receptacle and to the 35 hollow trunnion for feeding fluid to the interior of the receptacle, and a mixer element rotatable within the receptacle and exposed therein to the pressure of the fluid supplied by said pressure pipe, said mixer 40 element and the pressure pipe being movable with said receptacle in the operation of discharging a mixed mass from the latter.

9. In a concrete batch mixer, a receptacle for a batch of concrete material, means for 45 feeding fluid under pressure to the interior

of said receptacle and into said batch of such concrete material, and a rotary mixer element mounted within the receptacle, said mixer element being provided with paddles whose path of movement is adjacent to the 50 path of the inflowing fluid, whereby the full energy of the inflowing fluid is utilized for imparting rotary motion to said mixer element and in effecting the agitation of the components of the batch of concrete. 55

10. In a mixer, the combination with a suitable receptacle, of a fluid supply means connected therewith and adapted for directing upwardly within said receptacle a fluid under pressure, and an agitator mounted for 60 rotation on a horizontal axis within said receptacle, said agitator having blades in the line of flow of the fluid under pressure and adapted to be rotated by the impact of such fluid. 65

11. In a mixer, a receptacle provided with a curved bottom, a tubular member connected to said receptacle for feeding fluid pressure through said curved bottom, and a rotary agitator element mounted within said 70 receptacle, having its axis of rotation at approximately the center of the arc of said curved bottom, said agitator element having blades positioned in the line of flow of the fluid pressure and exposed thereto so as to 75 be rotated by such pressure, combined and operating for the purposes set forth.

12. In a mixer, a vessel, an agitator rotatable therein, and means for feeding fluid under pressure upward into contact with 80 said agitator and into a mass of material contained within the vessel whereby the agitator is rotated by impact of the fluid pressure, said fluid supply means and the agitator operating conjointly to impart motion to the material for effecting the admixture of the components of said mass. 85

In testimony whereof I have hereto signed my name this 25th day of April, 1924.

KARL R. SCHUSTER.
